Primary Examiner — Cynthia Ramirez*Assistant Examiner* — Gino Colan(74) *Attorney, Agent, or Firm* — patenttm.us(57) **CLAIM**

The ornamental design for a combined bath mixer pop-up waste and overflow, as shown and described.

DESCRIPTION

FIG. 1 is a perspective view of a combined bath mixer pop-up waste and overflow showing my new design;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof;

FIG. 8 is an operational perspective view thereof with bathtub; and,

FIG. 9 is an enlarge perspective view thereof with bathtub. The broken lines shown in the figures are included for the purpose of illustrating environment and form no part of the claimed design.
